[57] **CLAIM**

The ornamental design for a flexible computer video monitor anti-glare hood, as shown and described.

DESCRIPTION

FIG. 1 is a bottom plan view of a flexible computer video monitor anti-glare hood showing my new design;

FIG. 2 is a front elevational view thereof;

FIG. 3 is a top plan view thereof;

FIG. 4 is a side elevational view thereof;

FIG. 5 is a perspective view thereof in a folded condition;

FIG. 6 is a front perspective view thereof showing the design conforming to a rectangular monitor which is shown in broken lines;

FIG. 7 is a rear perspective view of FIG. 6;

FIG. 8 is a front perspective view thereof showing the design conforming to a different monitor shape;

FIG. 9 is a rear perspective view of FIG. 8;

FIG. 10 is an enlarged front elevational view of FIG. 8 showing the detailed appearance of the grooves;

FIG. 11 is a front perspective view thereof showing the design conforming to another monitor shape;

FIG. 12 is a rear perspective view of FIG. 11;

FIG. 13 is a front perspective view thereof showing the design conforming to another monitor shape;

FIG. 14 is a rear perspective view of FIG. 13; and,

FIG. 15 is an enlarged front elevational view of FIG. 13. The broken lines are shown in views for illustrative purposes only and form no part of the claimed design.
